(57) **CLAIM**

The ornamental design for a stand for television receiver as shown and described.

DESCRIPTION

1. Stand for television receiver

1.1 : Front perspective

1.2 : Back perspective

1.3 : Front

1.4 : Back

1.5 : Left

1.6 : Top

1.7 : Bottom

1.8 : Reference

1.9 : Reference

Reproduction 1.8 shows a state of the rear stand being folded; reproduction 1.9 shows a state of use being attached to the wall; a right view is omitted because it is a mirror image of the left view, the broken lines in reproduction 1.9 showing a wall depict environment that forms no part of the claimed design; all remaining broken lines shown in the reproductions depict portions of the stand for television receiver that form no part of the claimed design: the shading lines are used to show the surface of the claimed design and do not represent its surface ornamentation.
